GRID PLATE CASTING MACHINE

Arthur D. Lund, Minneapolis, Minn., assignor to
 Solar Corporation, Milwaukee, Wis., a corpora-
 tion of Delaware

Application May 17, 1947, Serial No. 748,679

6 Claims. (Cl. 22—92)

1

This invention relates to improvements in machines for casting storage battery grid plates and the primary object is to provide a machine which is comparatively simple but highly efficient in operation and adapted to produce cast battery plates at a high rate of speed and in accordance with modern production methods.

Another object of the invention is to provide a machine of this nature embodying stationary and movable molds adapted to be brought together during the casting operation and having matrix surfaces into which the molten metal may be poured while the molds are together and then allowed to cool. The movable molds are carried by reciprocating mechanism which moves them toward and away from the stationary molds so that as the plates are cast and cooled, they may be removed automatically as the molds separate. In accordance with my invention the movable molds ordinarily travel through a comparatively short working stroke toward and away from the stationary molds but I further provide mechanism under manual control which enables me to draw the movable molds through a wide opening stroke to positions widely separated from the stationary molds. When the molds are so separated convenient access to their faces may be had and they may be smoked or otherwise treated as is necessary in the operation of the machine, as will later become apparent herein.

Still another object of my present invention is to provide an improved mounting arrangement for the movable molds which embodies platens or mounting plates whereon the molds themselves are fastened and from which the molds may be removed at any time. The platens, in turn, are yieldably supported on the reciprocating mechanism in such manner as to enable the molds to properly register with the stationary molds as they come together and it will thus be seen that the movable molds may be taken off for replacement or other work without in any way disturbing these yieldable mountings and the adjustments thereof.

The above and other important objects of my invention and advantages thereof will be made apparent in the course of the following specification wherein reference is had to the accompanying drawings in which—

Fig. 1 is a side view of a machine embodying my invention showing the molds in the closed position and with intermediate parts of the delivery system for the cast plates broken away.

Fig. 1A is an enlarged detail sectional view of

2

the connections between the movable mold and its supporting platen.

Fig. 2 is a plan view of the machine as shown in Fig. 1 and again with the certain parts broken away.

Fig. 3 is a vertical cross sectional view through the machine taken along the line 3—3 in Fig. 1.

Fig. 3A is an elevation of one of the grid plates as cast by my machine.

10 Fig. 4 is a sectional detail view of the actuating and timing cams and taken substantially along the line 4—4 in Fig. 5.

Fig. 5 is an end view of the machine with parts of the delivery mechanism shown in vertical section along the line 5—5 in Fig. 1.

15 Fig. 6 is a longitudinal vertical section along the line 6—6 in Fig. 3 and here again showing the molds in their closed positions by showing also in dotted lines the positions assumed by 20 certain of the parts when the movable molds are drawn back to the fullest extent for smoking or other treatment.

Fig. 6A is a fragmentary detail section and plan view of the ram stop and taken along the lines 6A—6A in Fig. 6.

25 Fig. 7 is an enlarged detail end elevation of the actuating and regulating mechanism for the metal feed as viewed substantially along the lines in Fig. 1.

30 Fig. 8 is a fragmentary sectional view along the line 8—8 in Fig. 9.

Figs. 9A, 9B and 9C are fragmentary side elevational views partially in section and illustrating 35 progressive certain operations of the metal feed mechanism.

Fig. 9 is taken along the line 9—9 in Fig. 7 while Figs. 9A, 9B and 9C are taken substantially along the line 9A—9A in Fig. 7.

40 Fig. 10 is a fragmentary detail sectional view of the upper part of one stationary mold and adjacent edge of the melting pot and showing also the ladle and illustrating the dumping operation thereof.

Fig. 11 is an enlarged vertical and longitudinal sectional view through a part of the actuating means for the ram control valve and illustrating the manual override latch and operating handle therefor.

45 Fig. 12 is an enlarged side view partially in section of the movable and stationary molds detailed from other parts of the machine. This view is taken substantially along the line 12—12 in Fig. 13.

50 Fig. 13 is a face elevational view of the movable

mold but showing the cooling manifold partially in section.

Fig. 14 is a horizontal section along the line 14-14 in Fig. 13.

Fig. 15 is a detailed sectional view along the line 15-15 in Fig. 14.

Fig. 16 is an enlarged detailed section along the line 16-16 in Fig. 12.

Fig. 17 is an enlarged detailed section taken along the line indicated at 17 in Fig. 13.

Referring now more particularly and by reference characters to the drawing, my improved machine comprises a main or base frame, designated generally at A (and the construction of which will later appear), adjacent one end of which is a melting pot B for containing the molten metal such as lead. For convenience, this end of the machine will be hereinafter referred to as the forward end. The stationary and movable molds C and D are positioned in casting 20 position adjacent the pot B and it will be noted that there are two of both molds so that the machine each operation casts two complete grid plates.

The frame A has side castings 20 supported upon base sills or channels 21 and the upper edges of the side castings support longitudinal slides or rails 22 wherein is slidably mounted the lateral edges of a ram support plate or carriage 23. The carriage is thus supported for back and forth movements with respect to the stationary molds and for so operating the carriage I provide a main hydraulic ram or fluid motor 24 comprising a cylinder 25 secured by bolts 26 to bars 27 joining cross members 28 which extend between the side castings 20. The ram further includes a rearwardly extending, fluid actuated plunger 29 which is secured by a nut 30 to a depending cross flange 31 upon the rear end of the carriage 23. Fluid under pressure from a supply source (not shown) is supplied to the ram cylinder 25 through pipes indicated at 32, under control of a conventional piston-type control valve 33 having a handle 34, the arrangement being such that when the handle is moved in opposite directions from the neutral position (Fig. 1) the ram plunger 29 will be moved in opposite directions by the fluid. Thus the carriage 23 may be moved lengthwise along the frame A and held in any desired position as will be understood. The valve 33 is secured by bolts 35 upon a removably mounted valve supporting or mounting plate 36 on an upper rear corner of the machine, convenient for operation by an operator stationed alongside the machine.

Atop the carriage there are mounted in parallelism two reciprocatable mold actuating mechanisms or rams, designated generally at 37 and 38, respectively, and each comprises a base 39, the margins of which are beveled off and engaged by parallel slides or rails 40 secured by bolts 41 to the carriage. These rams 37 and 38 are thus supported for reciprocating movements in the same direction as, and independently of or with the carriage 23. The forward ends of the bases 39 have upwardly and then forwardly extending head portions 42 forming transversely extending openings 43 for a purpose later to appear, and the bases further have upstanding side webs 44 which at forward ends have outwardly or laterally turned mounting flanges 45. Secured by nuts 46 to the upwardly turned portions 42 are the forward ends of plungers 47 extending from hydraulic ram units or fluid motors 48 each of which has a cylinder 49 secured at its

rear end at 50 to an upstanding, transversely extending and rigidly braced web 51 upon the carriage 23. Front and rear ends of the cylinders 49 are respectively connected by cross manifolds or pipes 52 and 53 to the centers of which are in turn respectively connected flexible fluid supply lines 54 and 55 which are looped upwardly and extend to a control valve 56 secured at 57 upon the aforesaid valve mounting plate 36. This control valve 56 is also of the piston type and has a plunger 58 which is selectively actuatable by hand or by an automatic timing mechanism which will now be described. It will be understood, of course, that the rams 37 and 38 may be reciprocated simultaneously upon the carriage 23 by the alternate admission of fluid to opposite ends of the cylinders 49 through the supply lines 54 and 55 and connecting pipes 52 and 53.

Said automatic timing mechanism comprises a motor 59 which is mounted upon a base 60 carried on a slide 61 upon a bracket 62 secured at a lower forward corner of the frame A. A conventional variable speed pulley 63 is mounted on one end of the motor shaft and on the other end is a conventional magnetic brake 64. A transmission housing 65 and a conventional speed reducer unit 66 are mounted on a bracket 67 on the frame A and the drive pulley 68 for the unit 66 is connected by a belt 69 to the pulley 63 on the motor. A traversing screw is provided for the slide 61 and has a hand wheel 70 by which the position of the motor may be adjusted in a well known manner to regulate the effective diameter of the pulley 63 and make corresponding adjustments of the speed with which the unit 66 is driven by the motor. The output shaft of the speed reducer unit 66 is connected by a coupling 71 to a drive or cam shaft 72 journaled in the transmission housing 65 and, as seen in Fig. 4, there are two cams 73 and 74 mounted on this shaft within said housing. The cam 74 is fixed by its hub 75 on the shaft 72 while cam 73 is loose on the shaft and has arcuate slots 76 in which are positioned bolts 77 carried by cam 74. This arrangement causes the two cams to travel as a unit with the shaft 72 but allows the angular relationship of the cams to be relatively adjusted as will be apparent.

Also journaled in the housing 65 is a short rock shaft 78 whereon is secured a lever 79 having a roller 80 which rides the periphery of the cam 73. Externally of the housing the rock shaft 78 has secured thereto a lever 81 and engaged with this lever (Fig. 1) is a retractile coil spring 82 which maintains the roller 80 in contact with the cam. A link 83 connects the lever 81 to an arm 84 which at its lower end is secured to a shaft 85 journaled transversely in and through the sides of the frame A. The upper end of arm 84 is forked and pivoted at 86 to a link rod 87 which extends forwardly alongside the frame and the forward end of the link rod is pivotally attached at 88 to an operating mechanism designated generally at 89, for the valve 56. Referring particularly to Fig. 11 it will be seen that the mechanism 89 comprises a stub shaft 90 secured to the forward end of the valve mounting plate 36, forwardly of the valve 56, and oscillatably mounted on this shaft is an arm 91 to which the link rod is connected. Attached to the arm 91 is a segment 92 having a notch 93 in its edge. A handle 94 is provided having spaced lower sides 95 which are loosely mounted on the shaft 90.

straddling the arms 91 and segment 92, and it is to this handle that the valve plunger 58 is attached, as designated at 96. A latch 97 is fulcrumed at 98 between the handle sides 95 and at one end has a hook 99 which normally engages the notch 93. The opposite end of the latch is connected at 100 to the lower end of a thumb-piece rod 101 projecting upwardly through the handle and a spring 102 is positioned to urge the hook 99 into the notch. Thus normally the handle establishes a connection between the link rod 87 and the plunger 58 such that the endwise movements of the former, caused by the obvious operation of the cam 73, will be translated to similar but opposite movements of the plunger to actuate the valve 56 and so control the rams 37 and 38. On the other hand, by depressing the thumb-piece 101 the latch 97 will disengage the segment 92 and the handle 94 may be moved by hand to actuate the valve, independently of the automatic, timed and cam controlled movements of the link rod 87. The large end notch 103 in the segment 92 provides clearance for the connection 96 when the automatic control is released and this manual override used, as will be evident.

The molds D and C are similar in that they have mating matrix surfaces (see Fig. 13), which are so shaped and formed that when molten material is poured between the molds it will take on the shape of the desired battery plate. Since the exact formation of these matrix surfaces is not a part of the present invention it will not be described in detail herein, it being sufficient merely to note that the molds have upwardly opening mouths extending almost the full width of the matrices to receive and guide the molten metal down thereinto. The molds further have manifolds, designated generally at 104, through which a cooling fluid may be circulated to cool the plates as they are cast.

The stationary molds C are mounted side by side upon an end casting 105 which forms a rigid forward and upper part of the frame A and to so mount the molds they are provided at their lateral edges with notches 106 into which project the edges of large washers 107 placed on studs 108 which project rearwardly from the casting 105. By drawing up nuts 109 on the studs the molds may be readily clamped to the casting and it will be evident that the nuts are exposed for removal whenever necessary to change the molds, without the operator coming into contact with the hot melting pot B. The molds C further rest at lower edges upon set screws 110 (Fig. 6) projecting upwardly from toes 111 on the casting 105 and by adjusting the screws the molds may be leveled and registered properly with the movable molds.

The movable molds D are fastened to cushioning and support platens 112 which in turn are supported on the heads of the rams 37 and 38. The platens 112 have studs 113 secured to their rear faces at spaced points and, as best seen in Fig. 1A, these studs are locked by nuts 114 and extend loosely back through apertured cups or sockets 115 formed integrally on the flanges 45 of the rams. Expansion coil springs 116 are placed in the sockets 115 around the studs 113 and urge the platens forwardly with respect to the rams, this movement being limited, and the spring tension adjusted by stop nuts 117 on the rear ends of the studs, which nuts are locked by lock nuts 118. The platens 112 are further supported upon forwardly turned feet 119 on the 75

rams 37 and 38 and the platens and these feet have wear plates 120 and 121 secured respectively thereto, permitting slight forward and rearward movements of the platens with respect to the rams, as will be understood.

The molds D are then merely secured to the platens 112 by cap screws 122 at appropriate points and it will be evident that the molds may be removed from the machine at any time without disturbing the adjustments of the cushioning springs 116 which, once adjusted to bring the molds D up against the molds C with even pressure at all points, will need no further adjustment.

15 The molds C and D so operate that as the movable molds draw away from the stationary molds they carry along the completed plates and I accordingly provide means to knock or push these plates loose from the movable molds so that the plates will drop clear for transfer away from the machine by a conveyor mechanism which will be later described. For disengaging the cast plates from the movable molds D at the proper time a series of knock-out pins 117 are provided 20 at strategic points about the face of the molds and as best shown in Fig. 15, these pins are slidably positioned in openings 118 through the molds and project rearwardly therefrom into spring housings or cages 119 secured at 120 to the molds. 25 Within the housings 119 there are provided expansion coil springs 121 which bear rearwardly upon stop collars 122 on the pins and urge them rearwardly so that the forward ends normally stand flush with the matrix surfaces of the molds. 30 The knock-out pins, however, project rearwardly through plugs 123 on the housings 119 and for contact with these rearwardly projecting ends of the pins I provide a series of adjustable abutments or stops indicated at 124. These abutments 124 are screwed into cross-bars 125 which are secured at 126 to brackets 127 mounted upon the slide rails 40 adjacent the forward ends thereof. The brackets are bolted at 127a to the said rails and the bars 125 are fitted through the openings 43 at the forward ends of the rams 37 and 38. It is for the purpose primarily of providing clearance for these cross-bars 125 that these openings 43 are formed in the rams and it will be readily understood that by proper adjustments of the abutments 124, they may be arranged to contact the rearward ends of the knock-out pins 117 when the rams have drawn the movable molds D away from the stationary molds C through a predetermined distance. In practice, these adjustments will be made so that just prior to the time when the plungers 47 reach the limit of their rearward travel in the cylinders 49 the knock-out pins 117 will be engaged and thrust forward a short distance necessary to force the cast plates from the molds. It may here be noted that the plungers 47 come to rest against stops at both the rearward and forward limits of their travel and the aforesaid cushioning springs 116 permit the necessary slight rearward movement of the movable molds D as they come up against the stationary molds C at the end of each forward stroke of the plungers.

65 The molten metal from the melting pot B is poured in a predetermined quantity between the molds each time they come together and for this purpose I provide ladles, indicated generally at 128, and mechanism later to be described which periodically lifts the ladles from the filling positions of Fig. 6 to the dumping positions indicated in dotted lines in Fig. 10 whereat the ladles de-

liver the metal into the mouths of the molds. Referring particularly to Figs. 6 and 12 it will be noted that the upper inner faces of the molds are cut away and diverge upwardly for almost the full width of the matrix surfaces and as indicated at 129 to receive the metal.

In the operation of the machine as thus far described it will be apparent that as the movable molds D come up against the stationary molds C molten metal to a quantity sufficient to completely fill the matrix surfaces will be delivered by the ladles 128 between the molds and will quickly cool to form the cast plates. The movable molds D are moved forward to this casting position by operation of the rams 37 and 38 under control of the valve 56 which in turn is controlled by the cam 73, and it is possible by proper design of this cam to allow the molds to dwell in closed positions long enough to permit the necessary cooling action. When this time is past after each plate is cast the cam 73 will then reverse the position of the valve 56 to move the rams 37 and 38 rearwardly and separate the molds and as this movement is completed the abutments 124 will engage the knock-out pins 117 to thrust the cast plates from the movable molds. The cycle will then be completed by a forward movement of the rams to again bring the molds into casting positions. This operation may be carried out continuously and quite rapidly but in practice it is found that at intervals it is necessary to smoke or otherwise treat the matrix surfaces of the molds to insure the formation of perfect castings and proper stripping thereof. When this is necessary the operator, by actuation of the valve handle 34, may so adjust the valve 33 as to operate the main ram 24 to move the entire carriage 23 rearwardly and bring the movable molds D into positions widely spaced from the stationary molds as indicated in dotted lines in Fig. 6. Thus, while the normal casting operation is carried out by comparatively short strokes of the rams 37 and 38 to save time, I am able whenever necessary to increase the spacing between the molds to several times the normal spacing and thus allow convenient access to their faces for inspection and smoking or other treatment.

Whenever the wide opening of the molds is necessary for the reasons just given the operator will halt the operation of the rams 37 and 38 and to obtain the maximum opening the rams will be left in their rearmost positions as will be readily apparent. To bring this about, it is necessary to override the automatic cam controlled and timed actuation of the valve 56 and for this purpose the latch 97 is disengaged from the segment 92 by actuation of the thumb-piece 101 so that the valve may be controlled by the handle 94, all as previously described. However, it will be understood that if the rams were stopped at the very end of their rearmost stroke the knock-out pins 117 would be engaged by the abutments 124 and would be held in positions projecting forwardly from the matrix surfaces of the molds D. This is undesirable since the exposed ends of the pins might be injured at this time and I accordingly provide a selective stop for the rams by means of which they may be halted short in their rearward travel. This stop comprises a shaft 130 which extends transversely just forward of the flange 51 and which is journaled in bearing ears 131 thereon. At its center, this shaft 130 has a radially extending pin 132 and normally the shaft is rotated in a clockwise direction as viewed in Fig. 6 so that

this pin comes to rest upon a stop screw 133 in the carriage 23. The shaft is so biased by a torsional coil spring indicated at 134 in Fig. 2. Either end of the shaft may be provided with a handle 135 by which the shaft may be rotated through an arc of approximately 90 degrees in a counter-clockwise direction against the tension of the spring 134 and until the stop finger 132 engages a stop screw 136 located in flange 51. As seen in Figs. 6 and 6A, the tail ends of the rams 37 and 38 have rearwardly projecting lugs 137 and located in the path of the rear ends of these lugs the shaft 130 has flats 138 and 139 located at right angles to each other. In the normal position of the shaft 130 the flats 138 are turned forwardly toward the rams and these flats are so located that the lugs 137 will just clear them as the rams 37 and 38 move rearwardly to their extreme rearward positions. However, when the shaft 130 is turned by the handle 135 to bring the flats 139 to forward positions they will contact the lugs 137 before the rams reach such positions due to the fact that these flats are located forward of the axis of the shaft. In operation then, the operator will first allow the rams to come back far enough to eject the last plates cast before the inspection or treating operation and will then, by actuation of the valve handle 94, move the rams forwardly and lift the handle 135 so that on the next rearward or return motion of the rams, they will be stopped short a slight distance necessary to keep the abutments 124 from actuating the knock-out pins 117.

Referring now more particularly to Figs. 1, 2 and 7 through 10, the operation of the ladles 128 will be described in detail. Since the actuating mechanisms for each ladle are substantially identical only one will be described and similar reference numerals will indicate corresponding parts for the other.

Mounted on the end casting 105 is a bracket 140 having transversely spaced ears 141 wherein is fastened a shaft 142. From the innermost ear 141 there projects upwardly a fixed lug 143 and an adjustable stop screw 144 is mounted therein. Oscillatably mounted on the shaft 142 by a long sleeve bearing 145 is the upper part of a parallel-motion linkage indicated generally at 146 and which acts as a carrier and includes inner and outer arms 147 and 148 having bearings 149 and 150 aligned axes parallel with the bearing 145. A shaft 151 is journaled through and between the bearings 149 and 150 and at its inner end this shaft has a fitting 152 in which the cranked supporting arm 153 of the ladle 128 is clamped. The ladle thus travels with the shaft 151.

Spaced ears 154 and 155 are carried by a short sleeve 156 which is rockably mounted on the shaft 151 adjacent the outer bearing ear 150 and pivotally attached at 157 between these ears, eccentric to shaft 151, is the upper end of an actuating rod 158. The lower end of the actuating rod 158 (Fig. 1) is pivoted at 159 to one arm 160 of a bell crank lever 161 which is fixed on a rock shaft 162 journaled transversely through the frame sides 20. The opposite end of the shaft 162 carries a corresponding crank lever for simultaneously actuating the ladle mechanism on the opposite side of the machine. The remaining arm 163 of the bell crank lever 161 has pivotally attached thereto at 164 the forward end of a connecting rod 165 and the rear end thereof is pivoted at 166 to a crank

lever 167. This lever 167 has a shaft 168 journaled in the housing 65 and interiorly thereof (Fig. 4) the shaft carries an arm 169 on the end of which is a roller 170 adapted to ride the periphery of the cam 74. A spring 171 (Fig. 2) is connected between the end of the lever 167 and the frame side 20 at 172 and holds the roller 170 in engagement with the cam 74, as will be apparent.

Supported on the upper, forward part of the housing side 20, below and forwardly of the bracket 140, is an outwardly projecting stub shaft 173 and oscillatably mounted thereon is the lower arm of the aforesaid parallel-motion linkage, designated at 174. This arm 174 is forked at its upper end 175 (Fig. 7) and pivoted in the fork at 176 is the lower end of a parallel-motion link 177. The pivot axis 176 is spaced from the axis of shaft 173 the same distance as the spacing between the axes of the shaft 142 and 151. A projecting ear 178 on the arm 174 serves as the anchor point for the lower end of a retractile coil spring 179 and the upper end of this spring is connected to a short link bar 180 which is pivotally attached at 181 to the inner ear 155. The spring thus exerts a downward pull on the ears 154 and 155 forward of the axis of the shaft 151 so that the ears and attached sleeve 156 tend to turn clockwise on the shaft at all times. This movement is normally limited by the engagement of a stop surface 182 on the outer ear 154 with an abutment 183 on the arm 148, as seen in Figs. 9A and 9B particularly.

The upper end of the link 177 has integrally formed therewith a bearing sleeve 184 which journals on the shaft 151 inwardly of the sleeve 156 forming the pivot connections completing the parallel-motion linkage on the axes of the elements 141 and 151, and 173 and 176. Also positioned on the shaft 151 and keyed thereto at 185 (Fig. 8) are a pair of spaced sleeves 186 and 187 between which fits the sleeve 184. These sleeves 186 and 187 are connected by and support a stop bar 188 and the sleeve 184 has a tapped projecting lug 189 in which is threaded a screw 190 adapted to bear on this stop bar (Fig. 9). The screw 190 has a knurled knob 191 by which it may be adjusted by hand and has a conventional spring locking or detent mechanism 192. The stop bar 188 also lies in the path of an abutment or stop surface 193 on the ear 155 (Figs. 9B and 9C). A retractile coil spring 195 is stretched between a lug projection 196 on the sleeve 186 (opposite the stop bar 188) and a connection 197 on the lower end of the link 177.

In what may be called a normal or starting position for the ladle operating mechanism the parts assume the positions shown in Figs. 1 and 9A, and in such position the ladles 128 are lowered into the melting pot B below the level of the molten metal therein as seen in Fig. 6. The rotation of the cam 74 will now periodically actuate the roller 170 to swing the lever 167 to the left as viewed in Fig. 1 thus exerting a pull upon the connecting rod 165 such as to turn the bell crank lever 161 and attached rock shaft 162 in a counterclockwise direction. The actuating link 158 will thus be thrust upwardly and from the starting position of the parallel-motion linkage this upward movement of the link will be transmitted through the ears 154 and 155 to the shaft 151 to swing the upper arm part 146 of the linkage in a counter-clockwise direction as will be understood. This movement will continue until

the abutment 193 on the ear 155 contacts the stop bar 188 as seen in Fig. 9B at which point the shaft 151 will have been moved upwardly to the uppermost limit of its travel. This movement 5 151 will, of course, swing the ladles 128 upwardly and rearwardly out of the melting pot B to a position over the stationary molds C at which point this travel movement of the ladles will cease. During such movement, however, the 10 ladles have lifted a quantity of molten metal from the melting pot and it will be understood that since this movement of the ladles is controlled by the parallel-motion linkage, it will be accomplished without any tilting action of the ladles 15 such as would cause them to spill any of their contents.

The upward travel of the actuating link 158 continues past the point seen in Fig. 9B and in so doing now swings the ears 154 and 155 about the axis of the shaft 151 to the position shown 20 in Fig. 9C. This motion of the ears 154 and 155 is, however, transmitted to the shaft 151 through the engagement of the abutment 193 with the stop bar 188 so that the shaft itself is turned 25 through a part of a turn in a counter-clockwise direction after it has reached the aforesaid upper limit of its swinging motion. This rotary motion of the shaft 151, through its cranked connection 198 with the fitting 152, then serves to 30 tip the ladle 128 to its dotted line delivery position as shown in Fig. 10 so that the contents of the ladle will be delivered between the molds. Upon the return downward movement of the 35 actuating link 158 the ears 154 and 155 will first turn back in a clockwise direction until the stop bar 188 reaches its normal position against the stop screw 190 under the influence of the spring 195. This will return the ladle 128 to its normal position, seen in full lines in Fig. 10, and a continuation of the downward movement of the link 40 will then pull the shaft 151 and associated parallel-motion linkage back to starting position due to the contact of the stop surface 182 with the abutment 183. This completes the cycle of operation 45 and returns the ladle to the melting pot to gather a new load of molten metal.

The spring 179 serves to normally bias the ears 154 and 155 in a clockwise direction and so maintain the stop surface 182 in contact with the abutment 183 as will be readily understood. The 50 tipping motion, therefore, is carried out against the resistance of the spring 179 in the translation of the parts from the positions Fig. 9B and Fig. 9C, and the purpose of the link bar 180 is to allow this further or tipping motion of the ears and attached elements while keeping the line of tension of the spring forwardly of the axis of the shaft 151 so that the ears will be restored to their 55 normal positions and the ladles returned to their normal operating angle. The function of the spring 195 is to bias the stop bar 188 also in a clockwise direction and cause it to follow the motion back to its normal position of Fig. 9 after 60 the ladles have been tipped. It will be apparent that the angle of the ladle 128 may be adjusted by slightly turning the shaft 151 with respect to the parallel-motion linkage and it is for the purpose of making this adjustment that the screw 65 190 is provided. Obviously, as viewed in Fig. 10 if this screw is backed off, the stop bar 188 may be turned slightly in a clockwise direction to change the ladle angle and vice versa. The aforesaid uppermost limit of travel of the shaft 70 151 with the parallel-motion linkage is set and

limited by the stop screw 144 which engages an abutment 199 on the arm 147 as seen in Fig. 9.

Each ladle 128 has a wide cupped bottom portion 200, the ends of which are closed by the crank connection 153 and by a flange 201 so that as the ladle is lifted from the pot a quantity of molten metal will be carried upwardly in this cupped bottom. It will be noted that the forward edge 202 of the ladle stands considerably below the rear edge 203 over which the material 10 will spill as it is poured into the mold and thus that it is important that the angle of the ladle does not change as it is lifted from the melting pot. Otherwise, material would spill from this lowermost edge and it is, of course, for this reason 15 that I employ the parallel-motion linkage for controlling the travel of the ladle. Obviously, too, the angle at which the ladle is adjusted by the screw 190 will vary the level of the edge 202 with respect to the edge 203 and so quite precisely 20 to control the amount of molten metal which the ladle will hold. The angular surfaces 129 of the stationary mold D terminates in an acute edge 204 which in turn meets a forwardly and downwardly sloping surface 205 overhanging the rear edge of the melting pot B as clearly shown in Figs. 6 and 10. The adjustment of the stop screw 144 is made so that the travel of the parallel-motion linkage will lift the ladle to a dumping position at which its edge 203 will just tip over the parting edge 204 of the mold to deliver the molten metal onto the surface 129 which will, of course, guide it between the molds. Any material which may spill upon the edge 204 will be directed by the overhanging surface 205 back 30 to the melting pot as will be readily evident. However, since the axes of the shaft 151 in the dumping position of the parts stands almost actually aligned with the edge 203 as indicated at the junction of the lines 206 and 207 in Fig. 10 the tipping or dumping action will cause the ladle edges 203 to turn over just rearwardly of the mold edge 204 so that there is little likelihood of spillage.

The movable molds D carry shields 208 which open forwardly and prevent any possibility of molten metal spilling rearwardly over the rams or other parts.

As the finished cast plates drop from the movable molds as previously described they are carried away by a conveyor mechanism which will now be described. As seen in Fig. 3A the plates P as they come from the molds have laterally projecting lugs L at the upper corner portions by which the plates may be carried and conveyed and as the plates leave the molds they drop edge-wise onto rearwardly and downwardly curving chutes 209 which are pivotally supported at upper ends at 210 between the frame sides 20 and near lower ends are adjustably mounted on the frame by cross rods 211 playing in slots 212 and having fastening nuts 213. The plates P further taper toward their lower edges as shown in Fig. 3A and it is these comparatively narrow lower edges which drop onto the chutes 209 and slide downwardly thereon. The chutes have side flanges or rails 214 which the lower sides of the lugs L will engage and thus the plates, as they slide down the chutes with contact along this lower margin of the plate and at the lugs, will be straightened and restrained against any tendency to twist. The plates then drop onto the upper rearwardly moving flight of conveyor belts 215 at right angles thereto. These belts 215 are mounted upon rollers 216 and 217 carried by a

conveyor frame 218 and the forward, lower end of this frame is notched at 219 to seat over a cross rod 220 extending between the frame sides so that the entire conveyor system may be readily withdrawn from the casting machine. The rear or delivery end of the conveyor frame is supported on a floor stand 221 whereon is a motor 222 connected by a sprocket chain 223 to a countershaft 224 journaled in the stand. Sprocket chains 225 then connect the countershaft 224 to the shaft of the roller 216 to drive the belt 215. The frame 218 also supports an apron plate 226 underneath the top flight of the belt.

The flanges 214 terminate some distance above the belt 215 and running immediately under the flanges are the upper spans of conveyor chains 227 operating at forward ends over sprockets 228 on the shafts of the forward belt rollers 217. At their delivery ends the chains 227 operate over drive sprockets 229 on the stand 221 and under tightener sprockets 230 and the shaft 231 carrying sprockets 227 is driven from the countershaft 224 through a sprocket chain 232. It will be noted that the inclination rearwardly of the belt 215 is less than that of the chains 227 so that the distance between the upper spans of these elements gradually increases. Furthermore the belt is much shorter than the conveyor chains as clearly shown.

In action as the plates P slide down the chutes 209 (see dotted line showing in Fig. 6) they will be engaged at lower edges by the belts 215 and carried rearwardly until the lugs L slide off the flanges 214 and drop onto the conveyor chains 227. The plates will then be carried on rearwardly, gradually straightening up until the plates drop from the rear ends of the belts, leaving the plates suspended by their lugs between the conveyor chains. The plates will then be carried on up out of the machine and will accumulate against a stop 233 atop the stand 231 for periodic removal from the conveyor. The chains 227 run at a slightly higher surface speed than the belts 215 to tend to straighten the plates, as will be understood.

The variable speed pulley 63 allows precise adjustments of the operating speed of the machine, while the adjustable connections 76 and 77 between the cams 73 and 74 allows the ram operation and ladle operation to be relatively timed and adjusted for proper synchronization. The magnetic brake 64 serves to stop the machine operation promptly when the motor 59 is switched off for any reason and allows the rams to be halted in any desired positions.

It is desirable when the machine is shut down to lift the ladles 128 from the melting pot so that they will not freeze into the metal as it cools, and also to be able to lift the ladles to an inoperative position while the rest of the machine runs, in making mold adjustments, etc. For this purpose I provide a cam 234 (Fig. 1) which is mounted on a shaft 235 on the side of the frame and operated by a handle 236. This cam may engage a roller 237 on the bell-crank lever arm 160 and has a curvature such that by turning the handle the cam will lift the arm 160 and elevate the ladles to about the position shown in Fig. 10. In such position the ladles will continue to tilt and so will dump their contents, and then remain clear of the melting pot until the handle 236 is again turned to restore the parts to working positions.

The mold filling mechanism, herein disclosed, is disclosed and claimed in my co-pending appli-

cation Serial No. 58,461, filed November 5, 1948.

It will be noted that the various controls, such as the valves 33—56, motor and drive units and handle 239 may be readily positioned upon either side of the machine. Thus, it is possible to arrange the machines in pairs, side by side, with the controls on facing sides of the aisle between machines so that a single operator may readily attend two machines.

I provide openings 238 in the plate lugs to facilitate further operations on the plates (as for example trimming as in the Automatic Plate Trimming Machine of my co-pending application, Serial No. 703,799 filed October 17, 1946) and to form these openings the movable molds D carry pins 239 urged forwardly by springs 240 as seen in Fig. 16 and adapted to engage round bosses 241 on the stationary molds. These and other important details of the molds per se are disclosed in my co-pending application, Serial No. 758,825, filed July 3, 1947, now matured into Patent No. 2,508,865.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. In a grid plate casting machine having a frame, a reciprocating carriage mounted on the frame and a reciprocating mold carrier mounted on the carriage for reciprocation relative to said carriage, a stationary mold fixed to the frame, a movable mold fixed to the mold carrier and movable upon reciprocation of both the carriage and the mold carrier toward and away from the stationary mold, a first fluid motor mounted on the carriage and connected to the mold carrier for reciprocating the carrier relative to the carriage and moving the movable mold toward and away from the stationary mold, and a second fluid motor mounted on the frame and connected to the carriage for reciprocating the latter relative to the frame and also moving the movable mold toward and away from the stationary mold.

2. In a grid plate casting machine having a frame, a reciprocating carriage mounted on the frame and a reciprocating mold carrier mounted on the carriage for reciprocation relative to the carriage, a stationary mold fixed to the frame, a movable mold fixed to the mold carrier and movable upon reciprocation of both the carriage and the mold carrier toward and away from the stationary mold, a short stroke fluid motor mounted on the carriage and connected to the mold carrier to move the carrier and the movable mold relative to the carriage through normal working strokes toward and away from the stationary mold, and a long stroke fluid motor mounted on the frame and connected to the carriage to reciprocate the latter along with the mold carrier and movable mold relative to the frame through a longer stroke away from the stationary mold.

3. In a grid plate casting machine of the character described, a frame, a stationary casting mold on the frame, slides on the frame, a carriage mounted in said slides for reciprocatory movements toward and away from said stationary mold, slide rails on the carriage, a mold carrier slidably mounted on said rails for reciprocatory movements with respect to the carriage and toward and away from the stationary mold, a movable mold fixed to the mold carrier, a support on the carriage, a fluid motor mounted on

the support and connected to the mold carrier and operative to move the carrier and movable mold toward and away from the stationary mold, a mounting member depending from the carriage, a mounting member on the frame, and a second fluid motor having a cylinder connected to one of said mounting members and a plunger connected to the other mounting member for moving the carriage and the mold carrier and movable mold relative to the frame and the stationary mold.

4. In a grid plate casting machine of the 1

4. In a grid plate casting machine of the character described, a frame, a source of fluid under pressure, a stationary casting mold fixed to the

15 frame, a cooperating movable casting mold, a carriage mounted on the frame, means on the frame slidably supporting the carriage for reciprocatory movements relative to the stationary mold, a mold carrier, means for fixing the mov-

20 a mold carrier, means for fixing the movable mold to said mold carrier, means on the carriage slidably supporting the mold carrier and movable mold for reciprocatory movements relative to the carriage and stationary mold to thereby alternately open and close the casting mold.

25 by alternately open and close the casting molds, a first fluid motor having a cylinder and extensible plunger, means connecting this fluid motor to the carriage and to the mold carrier for reciprocating the latter relative to the carriage, a second fluid motor having a cylinder and extensible plunger, means connecting this fluid motor to the mold carrier and to the carriage for reciprocating the mold carrier relative to the carriage, the mold carrier being provided with a mold for casting a casting.

30 second fluid motor having a cylinder and an
extensible plunger, means connecting the second
fluid motor to the frame and to the carriage for
reciprocating the carriage and mold carrier and
movable mold as one unit relative to the frame,
a movable

35 a manually operative valve connecting the said fluid source to the second fluid motor, a power operated rotary cam, an arm pivoted on the frame and having means engaging the cam whereby rotation of the cam will oscillate the

40 arm, a link rod connected to the arm, a valve connecting the fluid source to the first fluid motor and having a movable part operative to alternately admit fluid to opposite ends of the cylinder of said first fluid motor, and means connecting the link rod to move the said movable part of the valve.

45 5. In a grid plate casting machine having a

50 frame supporting a motor and a reciprocating mold carrier, a fluid motor mounted on the frame and connected to the carrier to reciprocate the carrier, a valve connected to said fluid motor and having a moving part adapted to control the flow of fluid to said motor, a handle oscillatably mounted on said frame and connected to the moving part of the valve, said han-

55 handle being adapted to operate the valve by hand, a segment member oscillatably supported by said frame and connected to and oscillated by said first mentioned motor, said segment member having a notch, and a latch carried by the handle
60 for releasably engaging said notch, whereby the handle and the segment may be connected for oscillation as a unit.

6. In a grid plate casting machine of the character described, a frame, a stationary casting mold on the frame, a cooperating movable casting mold, a carriage, means on the frame slidably supporting the carriage for reciprocatory movements relative to the stationary mold, a mold carrier, means mounting the movable mold on said mold carrier, means on the carriage slidably supporting the mold carrier and movable mold for reciprocatory movements relative to the stationary mold to thereby alternately open and close the casting molds, a first fluid motor having a cylinder and extensible plunger, means con-

necting this fluid motor to the carriage and to the mold carrier for reciprocating the latter, a second fluid motor having a cylinder and an extensible plunger, means connecting the second fluid motor to the frame and to the carriage for reciprocating the carriage and mold carrier and movable mold as one unit, a shaft, means journaling the shaft on the carriage, and a stop carried by the shaft and movable upon adjustment of the shaft into the path of the mold carrier as it is moved away from the stationary mold by the first fluid motor to thereby halt such movement of the carrier short of the point to which it would otherwise be moved.
